UNITED STATES PATENT OFFICE.

HARVEY C. RENTSCHLER, OF WILKINSBURG, PENNSYLVANIA, ASSIGNOR TO WESTINGHOUSE LAMP COMPANY, A CORPORATION OF PENNSYLVANIA.

ELECTRON-TUBE APPARATUS.

Application filed February 27, 1919. Serial No. 279,581.

To all whom it may concern:

Be it known that I, HARVEY C. RENTSCHLER, a citizen of the United States, and a resident of Wilkinsburg, in the county of Allegheny and State of Pennsylvania, have invented a new and useful Improvement in Electron-Tube Apparatus, of which the following is a specification.

My invention relates to electron tube apparatus, as is used in the receipt of wireless impulses, and it has for its object to provide apparatus of the character designated that shall cause a relatively large percentage change in the controlled currents with a relatively weak controlling current by virtue of the phenomenon of resonance.

Other objects of my invention are to provide apparatus of the character designated that shall be positive in operation and which shall maintain the desired operating characteristics over relatively long periods of time.

Fig. 1 of the accompanying drawing is a diagrammatic view of a detector tube, together with associated auxiliary circuits embodying a preferred form of my invention; Fig. 2 is a diagram illustrating the operating characteristics of a system of this character; and Fig. 3 is a sectional view of a tube illustrating the phenomenon of resonance potential.

Two types of inelastic impacts between electrons and atoms in certain monatomic gases and vapors have been found to exist. The first occurs when the colliding electron displaces an electron of the atom without removing it from the atom. That is, it moves an electron from one orbit to another in the same atom. The phenomenon of electronic displacement in the atomic system, without removal of an electron, is called resonance. The potential through which the colliding electron must fall to acquire the necessary velocity to produce such displacement is known as the resonance potential for the gas or vapor in question. The second type of inelastic impact occurs when the colliding electron removes an electron from the atom and produces ionization.

The phenomenon of resonance exhibited by argon and by certain metal vapors is now well recognized and exhibits itself as follows. If a three-electrode tube be filled, for example, with argon gas, at a given pressure, and electrons attempt to force their way therethrough, as from the hot cathode, it is

found that the action changes materially with different velocities of the electrons. At a given velocity, an electron either passes completely through an argon atom or rebounds therefrom with an elastic impact, being substantially unaffected thereby and producing substantially no effect thereon. As the velocity of the electron increases, it apparently approximates the velocity of the electrons within the atom or has some other critical relation thereto, as a result of which the impact becomes non-elastic and a large portion of the energy of the impacting electron is taken up in displacing an electron of the atom and its velocity is thereby decreased. The resultant electron velocity is relatively low so that such electrons are taken up by the adjacent grid or screen electrode. As the accelerating screen potential is raised higher and higher, the critical velocity is reached at a greater and greater distance therefrom, so that the resultant electrons move at higher and higher velocity when reaching the neighborhood of the screen. As a result, a larger and larger percentage thereof pass therethrough and reach the plate, affecting the plate current. At a certain point, the velocity of the electrons becomes so high before they reach the screen that a second non-elastic impact is produced, with the production of low-velocity electrons which are also drawn to the screen. This cyclical action goes on with an indefinite number of repetitions as the screen potential is raised until interrupted by extraneous phenomena.

I have found that use may be made of this phenomenon in producing a detector or amplifier that operates with extreme reliability and sensitiveness. I find that particularly favorable results may be secured by employing the intermediate screen for the control of the electron velocity and by maintaining the plate electrode negative with respect to this screen, so that the potential gradient between the screen and the plate prevents those electrons, the velocity of which has been seriously impaired by virtue of resonance, from reaching the plate. Said potential gradient is not sufficiently pronounced to prevent those electrons that have suffered merely an elastic impact or which have passed through a gas particle without material modification of their velocity from reaching the plate.

Referring to the accompanying drawing for a more detailed understanding of my invention, I show a detector bulb at 3, preferably filled with argon gas and containing a plate electrode 4, a filamentary cathode 5 and an intervening screen or grid 6.

The screen 6 is maintained positive with respect to the filamentary cathode 5 by a battery 7, and the filamentary cathode 5 is maintained at incandescence by an A battery 8. In like manner, the screen 6 is maintained positive with respect to the plate electrode 4 by a suitable battery 9, the receiving apparatus 10 of any desired form being connected in the latter circuit.

Incoming impulses, as from a suitable antenna 11, are superposed on the circuit by a suitable transformer 12, as is usual in the art, between the filamentary cathode and the screen. A condenser coupling instead of a transformer may also be used.

Having thus described the structure of apparatus embodying my invention, the operation thereof is as follows.

Referring to Fig. 3, let it be assumed that the potential of the screen 6 is such that an electron emitted from the cathode 5 is accelerated to such a velocity as to have a non-elastic impact at a point 20 adjacent to the screen. Certain of the electrons which have not suffered non-elastic impact pass through and impinge upon the plate 4, determining the plate current. Those electrons which had suffered a non-elastic impact at a point, such as 20, however, escape from this impact with relatively low velocity and are, therefore, taken up by the screen 6. Thus, there is a diminution in the electrons received by the plate 4 and, consequently, in the plate current. As the screen potential is raised, the acceleration of the electrons emitted from the cathode 5 is greater and greater and these electrons reach a velocity corresponding to non-elastic impact at a point such as 21, further from the screen. The electron therefore receives pronounced acceleration before reaching the screen 6 and may, therefore, pass therethrough and reach the electrode 4 so that the plate current is gradually increased.

With still further increase in the screen potential, the initial non-elastic impact may occur at a point 22 so that the electron again reaches the critical velocity corresponding to non-elastic impact at some such point as 23, adjacent to the screen. The electron is taken up by the screen, and, as a result, the plate current is again reduced.

This cyclical change in the plate current, with an increase in the screen-potential, obtains until extraneous phenomena intervene and prevent further electron action.

Referring to Fig. 2, the potentials of the screen, determining the initial velocities of

the electrons, are plotted as abscissæ against the plate current as ordinates and the effect of resonance is to cause the characteristic curve to assume the form shown, having peaks 15 and 16 and a minimum point or trough 17. The peak 16 may correspond to the conditions as described at the point 21 and the trough 17 as corresponding to the point 20.

Assume that the batteries 7 and 9 are so adjusted as to determine the screen potential at a value producing a given velocity of electrons such that there is either maximum or minimum disturbance thereof by the phenomenon of resonance. If there is a maximum disturbance thereof by screen potential, the number of electrons, the velocity of which is materially lowered, is a maximum and these electrons are turned back by the potential of the grid and never reach the plate electrode, thus causing a decreasing plate current. If, on the other hand, the screen potential is adjusted to establish an electron velocity such that there is minimum interference from the gas atoms substantially all electrons have such a velocity that they reach the plate electrode without difficulty, producing an increasing plate current.

Let it be assumed that the adjustment is such as to cause operation corresponding to the point 15 in Fig. 2. An incoming impulse of such polarity as to add to the potential of the battery 7 carries the total screen potential to a value 18 and the associated impulse of the other polarity partially neutralizes the voltage of the battery 7 and carries the screen potential to a point 19. Thus, the average effective plate current during the receipt of impulses is substantially of the value shown by the line 30-31, substantially midway between the line 19-18 and the point 15 and is sufficiently different from its normal value to produce distinct audition at the receiver 10, even with extremely weak incoming signals.

While I have described operation at a peak 15, the adjustment of the battery 7 may readily be made such that operation is secured at the trough 17 or at the peak 16. Obviously, with operation at the trough 17, the normal adjustment of the current is to a minimum value and the current increases with a potential increase on the screen or with a potential decrease.

I wish to direct particular attention to the fact that a bulb of the above-described character has definite peaks and troughs which may be used as operating points, as distinguished from certain bulbs of the prior art wherein the characteristic curves had merely knees. It will be noted that, when operating with a trough or peak, the average or effective current in the output circuit during the receipt of impulses is sub-

stantially one-half the total current variation, whereas, when operating on a knee, the effective current is substantially one-half the difference between the current increase and the current decrease.

The following marked distinction should be noted between the operation of a tube embodying the present invention and the ordinary three-element tube of the prior art. In the latter device, the grid or intermediate electrode performs merely a passive function so far as concerns giving velocity to the emitted electrons, in that the electrons emitted from the cathode move at sufficient velocity, due to the joint action of the cathode and anode alone, to carry them to the anode, either directly or indirectly, and the grid exerts a retarding influence, when of sufficiently low potential, thus determining the number of electrons reaching the plate electrode.

With the device of the present invention, however, the intermediate or screen electrode exerts an active velocity giving function, and the plate acts as the lower-potential control member just as in the prior art the intermediate or lower-potential member acts as a control.

In other words, with the tube of the prior art, the low potential of the intermediate grid electrode has been the controlling factor and little or no energy was taken therefrom, whereas, with the present tube, there is necessarily energy abstraction from the screen electrode and, accordingly, a flow of current thereto.

While I have illustrated the use of a bulb of the character described as a detector bulb for the receipt of wireless impulses, it will be obvious to those skilled in the art that it is susceptible of application in many other relations where it is desired to modulate a local current by a controlling current, as in amplifiers and other forms of apparatus.

A still further use of this invention is a frequency doubler, it being obvious that a change in the modulating potential from the point 19 to 18 and back again causes two modulations in the plate current, and this phenomenon may be made use of in various applications.

I contemplate the use of this invention in tubes which perform merely a relaying action with but little excess of modulated current over modulating current or as applied to tubes where there is a pronounced difference between the two currents and also as covering those tubes whose primary function is largely integration of high-frequency impulses.

While I have shown my invention in a preferred form, it will be obvious to those skilled in the art that it is not so limited but is susceptible of various minor changes and modifications without departing from

the spirit thereof and I desire, therefore, that only such limitations shall be placed thereon as are imposed by the prior art or are specifically set forth in the appended claims.

70

I claim as my invention:

1. In an electron tube, the combination with an electron source, of a plate electrode, and an intervening screen electrode, said tube being filled with a medium exhibiting 75 the phenomenon of resonance.

2. The combination with an electron tube provided with an electron source, a plate electrode, an intervening screen electrode and a filling of a medium exhibiting the 80 phenomenon of resonance, of means for maintaining said plate electrode at a positive potential, and means for modulating the potential of said screen electrode.

3. The combination with an electron tube 85 provided with an electron source, a plate electrode, an intervening screen electrode and a filling of a medium exhibiting the phenomenon of resonance, of means for maintaining said plate electrode at a positive potential, means for maintaining said screen electrode positive with respect to both of said remaining electrodes, and means for modulating the potential of said screen electrode.

95

4. An electron tube comprising an electron-emitting electrode, a screen and a plate in said tube and a gaseous filling for said tube, and means to give a periodic screen-potential plate-current characteristic with 100 values above zero.

5. An electron tube comprising an electron-emitting electrode, a screen, and a plate, means to give to said screen a potential positive with respect to said electrode and plate 105 and further means to give to the screen-potential plate-current a rising and then a falling characteristic, said falling characteristic followed by a rising characteristic and the whole of said characteristic never falling to zero.

110

6. An electron tube comprising an electron-emitting electrode, a screen and a plate in said tube and a gaseous filling for said tube, and means to give a periodic screen-potential plate-current characteristic with 115 values above zero, said means being adjustable so as to work said tube at a point of the characteristic when the slope sign of the characteristic changes.

120

7. The method of operating an electron tube having a screen-potential, plate-current characteristic with portions of positive and negative slopes and containing a medium exhibiting the phenomenon of resonance, which comprises adjusting the non-modulated screen-potential to a point of the characteristic where the sign of the slope changes.

125

8. In an electron tube, a filling of a 130

- medium exhibiting the phenomenon of resonance, electron-emitting and receiving means, and means whereby a controlling force modifies the velocity of said electrons so that the degree of retardation thereof by said medium is modified.
9. The method of operating an electron tube provided with electron-emitting and electron-receiving means, with a filling of a medium exhibiting resonance and with means for controlling the electron velocity, which comprises adjusting said last-named means for an electron velocity of maximum or minimum retardation by the resonance of said medium and thereafter modulating said last-named means.
10. An electron tube comprising an electron-emitting source, an electron-receiving source, means for modifying the electron velocity therebetween, and a filling of a medium exhibiting the phenomenon of resonance.
11. An electron tube comprising an electron-emitting source, an electron-receiving source, means for abruptly modifying the electron velocity therebetween, and a filling of argon gas, under such conditions as to exhibit the phenomenon of resonance.
12. An electron system comprising a tube provided with electron-emitting means, electron-receiving means, means for controlling the electron velocity abruptly therebetween, before reaching said electron-receiving means, a filling of argon gas under such conditions as to exhibit the phenomenon of resonance, means for applying the controlling effect in modifying said velocity-controlling means, and means for establishing a controlled current in accordance with the number of electrons reaching said electron-receiving means.
13. An electron system comprising a tube provided with an incandescing electrode, an electron-receiving electrode, an intervening perforated electrode, and a filling of argon gas, means for maintaining said electron-receiving electrode positive with respect to said incandescing electrode, means for maintaining said perforated electrode positive with respect to both of said remaining electrodes, means for controlling the potential of said perforated electrode, and means for establishing a controlled current in accordance with the electrons reaching said electron-receiving electrode.
14. An electron tube comprising an electron-emitting cathode, an anode and a grid therebetween, said elements being enclosed in a medium exhibiting the phenomenon of resonance and means for maintaining a constant potential difference between the anode and grid while applying a modulating influence between them and the cathode.
15. The method of operating an electron tube provided with electron emitting, controlling and receiving means in an atmosphere of a medium exhibiting the phenomenon of resonance, comprising applying constant potentials between said emitting, controlling and receiving means while impressing a modulating potential between the emitting means and the controlling and receiving means.

In testimony whereof, I have hereunto subscribed my name this 24th day of Feb., 1919.

HARVEY C. RENTSCHLER.

Certificate of Correction.

It is hereby certified that in Letters Patent No. 1,465,997, granted August 28, 1923, upon the application of Harvey C. Rentschler, of Wilkinsburg, Pennsylvania, for an improvement in "Electron-Tube Apparatus," errors appear in the printed specification requiring correction as follows: Page 1, line 30, strike out the word "potential", and line 75, for the syllable "ro." read *ve-*; page 3, line 68, for the word "thereon" read *thereupon*, and line 83, claim 2, for the misspelled word "potention" read *potential*; and that the said Letters Patent should be read with these corrections therein that the same may conform to the record of the case in the Patent Office.

Signed and sealed this 30th day of October, A. D., 1923.

[SEAL.]

KARL FENNING,
Acting Commissioner of Patents.
